(57) **CLAIM**

The ornamental design for a pair of earbud headsets, as shown and described.

DESCRIPTION

FIG. 1 is a front view of a pair of earbud headsets, with the right earbud for the right ear shown left facing and the left earbud for the left ear shown right facing whereby the ear hanger resides behind the ear, according to our new design; FIG. 2 is a back view shown in FIG. 1 thereof; FIG. 3 is a side view of FIG. 1 thereof; FIG. 4 is a side view of FIG. 1 thereof; FIG. 5 is a top view of FIG. 1 thereof; FIG. 6 is a bottom view of FIG. 1 thereof; FIG. 7 is a front perspective view of FIG. 1 thereof; FIG. 8 is a back perspective view of FIG. 1 thereof; FIG. 9 is a front perspective view of FIG. 1 thereof; FIG. 10 is a back perspective view of FIG. 1 thereof; FIG. 11 is a top perspective view of FIG. 1 thereof; and, FIG. 12 is a bottom perspective view of FIG. 1 thereof. The broken lines in FIGS. 1-12 immediately adjacent the shaded areas represent the bounds of the claimed design while all other broken lines are directed to environment; the broken lines form no part of the claimed design.
